D McRA LIVINGSTON, OF NEW YORK, N. Y.

SPRING SUSPENSION MEANS.

1,240,063.

Specification of Letters Patent. Patented Sept. 11, 1917.

Application filed June 17, 1916. Serial No. 104,199.

To all whom it may concern:

Be it known that I, D McRA LIVINGSTON, a citizen of the United States, and a resident of the city of New York, borough of 5 Manhattan, in the county and State of New York, have invented a new and Improved Spring Suspension Means, of which the following is a full, clear, and exact description.

10 The suspension means generally employed in automobiles, particularly the shackles employed in transverse spring-suspension means, permit a sidewise swaying of the spring-supported portion of the 15 chassis and its body, due to the endwise swaying of the springs on their shackles. In the swaying movement of the springs, the shackles have a parallel movement, that is to say, they swing in the same direction, 20 whereas in response to the flexure of the springs, the shackles move in opposite directions, that is to say, either toward or from each other.

The prime object of my invention is to 25 provide suspension means which will yield and respond to flexure of the spring but which will oppose endwise bodily swaying of the spring and hence prevent swaying of the spring-supported super structure.

30 Reference is to be had to the accompanying drawings forming a part of this specification in which similar reference characters indicate corresponding parts in all the views.

35 Figure 1 is a front elevation showing a transverse spring suspension having my invention arranged in connection with the shackles with which the ends of the spring are connected;

40 Fig. 2 is an enlarged fragmentary perspective view, showing an improved shackle; Fig. 3 is a view similar to Fig. 1 but illustrating a slight modification;

45 Fig. 4 is a sectional plan view on the line 4—4, Fig. 3.

In Fig. 1 is shown a known type of axle 10, together with a known super structure 11, the illustrated portion serving to receive a radiator (not shown), the super structure 50 being supported on a transverse spring 12 and secured by clips 13. The features referred to form no part of the invention and will vary with the type of car.

The springs arranged as shown in Fig. 1 55 are suspended usually by shackles 14, one end of each of which is connected with an

end of the spring 12, as at 15, and the opposite end usually is pivoted as at 16 on a standard 17 secured to the axle.

It is obvious that upon a flexure of the 60 spring 12, the shackles 14 will be swung away from each other upon a depression of the spring, or toward each other upon the rebound of the spring so that in both cases, the shackles will move in opposite directions 65 to each other. On the other hand, a bodily endwise swaying of the spring 12 and with it the supported super structure 11, will tend to swing the shackles 14 in the same direction on their pivots. 70

In accordance with my invention I prevent endwise swaying movement of the spring 12 by preventing the shackles 14 from swinging in the same direction on their pivots 16. For the purpose, each shackle 75 14 is provided with a lever arm 18, said arms extending inwardly, that is to say, toward each other, the said lever arms constituting with the shackle, a bellcrank lever in effect, the arm 18 of which has much 80 greater length than the arm represented by the shackle 14. In connection with the lever arms 18 I provide any suitable means that will so control said arms that they may yield to a movement of the shackles 14 in 85 opposite directions, that is to say, either toward or from each other, and therefore, permit the spring 12 to flex. A movement, however, of the shackles 14 in the same direction, that is to say, to the right or to the 90 left of Fig. 1, will result in reverse movements of the lever arms 18, since a movement of the left-hand shackle 14 to the left on its pivot 16 will throw the arm 18 of said shackle downwardly, whereas a movement of the right-hand shackle 14 to the left on its pivot 16 will throw the lever arm 18 of said shackle upwardly. 95

In the form shown in Figs. 1 and 2, the lever arms are made to control each other in 100 a manner to prevent movement thereof in opposite directions, use being made for this purpose of a slot and pin connection between the overlapped ends of the arms, there being slots 19 in the overlapped ends of the 105 arms 18 and bolts 20 extending through said slots, provided with nuts 21. Thus, while the arms 18 are free to rock in unison upwardly or downwardly, the one cannot move upwardly and the other downwardly, and 110 hence, the shackles 14 may not move simultaneously either to the left or to the right,

whereby the spring 12 and the spring-supported super structure 11 will be prevented from bodily swaying. If desired, cushioning springs 22 may be provided in the slots 19 at each side of the bolt 20.

It will be observed that a single arm 18 extends from each shackle 14, which thereby represents a fork of the said lever arm.

In the form shown in Figs. 3 and 4, a pair of separate shackles 14^a is employed at each end, each shackle having its separate arm 18^a so that there is a pair of lever arms at each end of the spring 12. It is to be understood that the elements 10 to 13 are the same as described in Fig. 1, and that the spring 12 is connected with the lower ends of the shackle as at 15^a, and the upper ends of the shackles are pivoted as at 16^a, to up-standing brackets 17^a, similar to the brackets 17.

In the form shown in Figs. 3 and 4, the inner ends of the arms 18^a are received in a boxing 19^a. Above the boxing 19^a are springs 20^a which abut at their upper ends against brackets 21^a secured to the supported super structure 11 at the center of the spring 12. Similarly, springs 20^b are provided at the under side of the boxing 19^a and seat on brackets 21^b secured to the axle 10. The construction supports the adjacent ends of the lever arms 18^a cushioning the same and taking care of any loose play at the pivots 15^a or 16^a, and bearing the weight of the lever arms. Like the construction first described, the lever arms 18^a are free to move in unison in upward or downward direction according to the direction of flexure of the spring 12, but the movement of the shackles 14^a simultaneously to the right or left, is prevented.

In both forms, the purpose is served of permitting the lever arms to assume varying relative angular positions and to slide one upon or relatively to the other, while at the same time they are tied to limit them to corresponding vertical movements.

Having thus described my invention I claim as new, and desire to secure by Letters Patent:

1. In a device of the class described, a vehicle spring, suspension shackles to which the ends of the spring are connected, levers connected with the said shackles and extending laterally inward therefrom, said levers

being arranged to rock vertically, and means acting on the levers and preventing movement thereof in opposite directions but yielding to movements of the levers in the same direction.

2. In a device of the class described, a vehicle spring, pivoted suspension means for the ends of the spring, lever arms rigid with the suspension means at each end of the spring, and means acting on the lever arms preventing movement thereof in opposite directions while permitting movements of the arms in a corresponding direction.

3. In a device of the class described, a spring, shackles suspending the spring at the ends, lever arms on the shackles extending toward each other, and means in connection with the inner ends of the arms opposing movement thereof in opposite direction while yielding to movements of the arms in a corresponding direction.

4. In a device of the class described, a spring, shackles suspending the ends of the spring, lever arms rigid with the shackles and constituting with said shackles, bell-crank levers, the said arms extending toward each other and having their ends overlapped, and means engaging the overlapped ends of the arms, said last-mentioned means opposing movement of the lever arms in opposite directions while yielding to movements of the lever arms in a similar direction.

5. In a device of the class described, a spring, shackles suspending the ends of the spring, lever arms rigid with the shackles and constituting with said shackles, bell-crank levers, the said arms extending toward each other and having their ends overlapped, the said overlapped ends being slotted, and a transverse bolt extending through the slots of the respective arms.

6. In a device of the class described, a spring, shackles suspending the ends of the spring, lever arms rigid with the shackles and constituting with said shackles, bell-crank levers, the said arms extending toward each other and having their ends overlapped, and spring-pressed means engaging the overlapped ends of the arms and preventing movements of the same in opposite directions while yielding to a movement of the arms in a similar direction.

D McRA LIVINGSTON.
